COMPRESSOR BLADE AND METHOD OF FORMING SAME

Elmer P. Warnken, Cincinnati, Ohio, assignor to Cincinnati Testing & Research Laboratories, Cincinnati, Ohio, a partnership

Application March 3, 1954, Serial No. 413,743

10 Claims. (Cl. 253—77)

This invention relates to rotor blades for turbines, compressors, blowers, or the like. More particularly this invention relates to compressor blades for axial flow compressors and to a method for making such compressor blades.

An object of this invention is to provide a compressor blade composed of a resin which is reinforced by elongated glass fibres that extend the length of the blade and are prestressed in tension so that the body of the blade is stressed in compression, thereby giving the body of the blade the strength required to carry the load caused by centrifugal force.

A further object of this invention is to provide a blade of this type in which the fibers extend lengthwise of the blade and are of folded doublet form, the fold of the doublet being at the root of the blade.

A further object of this invention is to provide a prestressed compressor blade having a core of prestressed lengths of fibre glass material and a skin around the material which skin is formed of a mixture of resin and short staple glass fibres, the prestressed lengths of fibre glass material stressing the resin and the short staple fibres in compression.

A further object of this invention is to provide a blade of this type in which a rigid pin extends the fold of the doublet so that the folded end is thereby rendered thicker than the remainder of the blade, and shaped to form a retaining key at the root end of the blade.

A further object of this invention is to provide a blade of this type in which the pin is a part of a slotted key member having a key portion and a pin portion spaced from each other by the slot and in which the lengths of fibre glass material extend through the slot of the key member.

And a further object of this invention is to provide a method of forming a prestressed blade having a core of lengths of resin-impregnated fibre glass material and a skin formed of resin and short staple fibres which includes the steps of disposing the lengths of material in an elongated mold, and, while in the mold, stressing the material in tension and injecting into the mold a mixture of resin and short staple glass fibres to impregnate and cover the lengths of material; and then curing the resin to form a hard, infusible prestressed resin blade and blade root.

The above and other objects and features of the invention will be apparent to those having ordinary skill in the art to which it pertains from the following detailed description, and the drawings, in which:

Figure 1 is a perspective view showing a compressor blade constructed in accordance with an embodiment of this invention;

Fig. 2 is a plan view of a mold for forming the blade;

Fig. 3 is a view in section taken on the line III—III in Fig. 2, prestressed rovings being shown in the mold in position after molding;

Fig. 17 is a sectional view showing the mold of Fig. 16 following injection;

Fig. 18 is an exaggerated sectional view of the blade illustrated in Fig. 13; and

Fig. 19 is a schematic view showing the arrangement of rovings and pin used in molding the blade shown in Fig. 1.

In the following detailed description, and the drawings, like reference characters indicate like parts.

In Figure 1 is shown a compressor blade 9 for an axial-flow air compressor, such as the compressor section of a jet aircraft engine. The blade 9 comprises a vane portion 10 of airfoil configuration and a root end portion 12 of generally tear drop shape. The blade is adapted to be mounted in a slot 13 in a rotor ring 14 of a compressor, as shown in Fig. 7.

The blade is formed of resin-impregnated fibre glass. The resin may be an appropriate phenol formaldehyde type, which, when cured, provides a hard infusible blade surface overlying the glass fibres, or may be a suitable epoxy resin or other suitable resin.

In the formation of the blade 9, lengths of elongated fibre glass material 16 (Fig. 19) of resin-impregnated glass fibres are arranged in doublets through the loop or fold of which a pin 17 extends. The material may be fibre glass fabric or woven cloth. Preferably, the material is in the form of elongated rovings which extend lengthwise of the blade. The fibres of the material may be coated with a thermo-setting resin by dipping the same in the resin. As indicated in Figs. 3 and 6, the material 16 and the pin 17 are placed in a lower mold member

18. The free or blade tip ends of the material are clamped to mold member 18 by means of a clamp plate 19 secured to member 18 by means of machine screws 21. When pin 17 is located in slots 22 and 23 in the mold member 18, the material is stressed in tension, as will be explained.

As indicated in Fig. 6, the distance A from the clamp plate 19 to the upper ends of the slots 22 and 23 is shorter than the distance B to the lower ends of the slots. Thus when

the pin 17 is advanced downwardly into the slots 22 and 23 the rovings are stressed in tension. When the material is stressed, a space 24 opens between the converging portions 24a and 24b of the rovings. A plug 24' of resin-impregnated glass fibres may be disposed in space 24 to provide material for filling this space when the blade is molded (see Fig. 19).

The mold member 18 is provided with a molding surface or face 25 which is of airfoil configuration for molding the vane portion of the blade. At the left hand end of the face 25 is provided a rounded mold portion 25' for molding one face of the root end of the blade. When the pin and fibre glass material are positioned in the mold, a movable mold member 26 is actuated by a ram 26' into the cavity of the lower mold member 18 against the material and the fold containing the pin 17, whereby the pin is forced into the bottom of slots 22 and 23 and the material is stressed in tension, and the resin is molded and set. When the plunger is raised, as indicated in Fig. 3, the resin holds the material in prestressed condition.

The lower face of the plunger 26 is provided with a mold cavity which mates with the molding face of the lower mold member to form the blade. While pressure is applied to the mold by ram 26', the prestressed material and resin are heated to sufficient temperature and for a sufficient time to cause curing of the resin, and the resin, when cured, holds the material in prestressed condition and forms a hard, smooth, infusible blade surface. After curing, the blade is removed from the mold and trimmed to the final shape of a finished blade as shown in Fig. 1.

In the finished blade, the tension of the fibre glass material stresses the resin of the blade in compression. Preferably the blade is prestressed to sufficient degree so that the prestress load on the blade is greater than the design load level to be produced in the blade in actual use. Thus, when the blade is mounted in the rotor ring 14 and in actual operation, the prestress load maintains a compression in the resin of the blade.

As shown in Fig. 1, ends 27 of the pin 17 project beyond the ends of the blade. The ends 27 may be retained, as shown in Fig. 1, or, if desired, the ends 27 may be trimmed off flush with the ends 28 of the blade (only one of which is shown).

The pin of the blade described to this point is shown as a round pin. If preferred, a pin of the form shown in Fig. 5 at 30 may be used instead of a round pin. The pin shown in Fig. 5 includes a main portion 32 of tear drop shape. At the ends of the main portion 32, integral rounded portions 33 and 34 are provided. The portions 33 and 34 are receivable in the slots 22 and 23 of the mold 18. When the pin of Fig. 5 is used, the blade is formed in the same manner as when pin 17 is employed, but in that case pad 24' is not required as the pointed portion 36 of the pin 30 fills the gap between the layers of material at the root end of the blade.

The blade illustrated in Fig. 1 is of particular use where a slot 13 of the special shape shown in Fig. 7 may be employed for receiving the root end of a blade. However, for some purposes, a blade 38 of the shape illustrated in Fig. 8 is more desirable because the blade illustrated in Fig. 8 can be used with rotors constructed to employ conventional blades. The blade 38 shown in Fig. 8 includes a metal pin member 39 (see Fig. 9). The pin member 39 includes a main portion 41 of tear drop shape, and root-strengthening rib members 42, 43, and 44. In the formation of the blade illustrated in Fig. 8, the pin 39 extends through the loop of the doublets of glass fibre rovings 46 or the like, in the manner shown in Fig. 10, and the rovings and pin are positioned in a mold, as shown in Fig. 11.

The mold of Fig. 11 includes a lower member 47 and an upper member 48. The mold contains a mold cavity 49 between members 47 and 48. The elongated rovings extend through an opening 51 at one end of the mold

cavity and are clamped by an appropriate clamp 52. The clamp 52 is urged to the right, as shown in Fig. 11, to prestress the rovings 46. When the rovings have been prestressed, a molding compound consisting of a mixture of resin and short stable glass fibres is introduced into the mold cavity through a gate 53.

The short staple glass fibres may be of relatively short length, say about one-half (1/2) inch, for example, whereas, the length of the elongated prestressed rovings is greater than the overall length of the finished blade. Preferably, both the elongated rovings and the short staple fibres are resin-coated or impregnated. The resin-impregnated short staple fibres are forced into mold cavity 49 under a very high pressure of the order of magnitude of two and one-half (2 1/2) tons per square inch so that the short staple fibres and resin are forced around and through spaces between the fibres of the prestressed rovings to form a body and outer skin or blade surface and filling a root end cavity 54 and encasing the pin 39. The mold pressure is sufficient to compact the resin and short staple fibres around the rovings to form a solid blade mass. While under pressure, the blade is heated to a sufficient temperature to set the resin and form a hard infusible blade mass. The molding compound preferably contains short staple glass fibres but may contain a resin and other suitable short fibres.

In the finished blade 38, the short staple fibres form a section 54 overlying and surrounding the prestressed rovings 46, as shown in Fig. 12. The prestressed rovings are thus stressed in tension in the finished cured blade, while the resin and short staple fibres in the vane portion 56 of the blade (see Fig. 8) are stressed in compression.

In Fig. 13 is shown a blade 61 having a rigid metal key and pin member 62 having an exposed metal key portion 63 which may be inserted in an appropriate key-shaped slot of a rotor. As shown in Fig. 14, the member 62 is provided with a slot 64. The slot 64 divides the member 62 into the key portion 63 and a pin portion 66 with the slot 64 therebetween. The portions 63 and 66 are connected together by end plate members 67 and by a sufficient number of bridging members 68 to maintain the members 63 and 66 in rigidly spaced relation. As shown, a portion of the member 63 is cut away, as indicated at 69, to form a gate through which resin-impregnated short staple fibres are injected during molding of the blade 61. The key and pin member is preferably formed of rigid forged metal or the like.

As shown in Fig. 15, resin-impregnated doublets 71 are formed upon the pin 66 with the folds of the doublets extending through the slot 64. The doublets may be of fabric but preferably are rovings of glass fibers. The key and pin member 62 and the doublets of rovings 71 are disposed in a mold 72, as indicated in Fig. 16. As shown in Fig. 16, the mold 72 includes a lower portion 73 and an upper portion 74 between which are formed two mold cavities 76 and 77. Free ends of the rovings 71 are clamped by means of clamps 78, and the clamps are urged away from the center of the mold to prestress the elongated rovings. Then, resin-impregnated short staple rovings are injected into the mold cavities through gate 79 to fill the mold cavities around the elongated rovings. As shown in Fig. 18, in the finished blade, the elongated rovings 71 are surrounded by a mass or skin of resin-impregnated short staple rovings 81. In Fig. 18, the mass 81 is exaggerated in size for clarity of showing.

The blade 61 includes an exposed metal member 63 of key shape which takes the stress on the key portion of the blade when the blade is in use.

The prestress load of each of the blades is preferably calculated to be sufficient so that the internal centrifugal force load of the blade during use is all taken by the prestressed elongated rovings, and the resin and short staple fibres remain under compression even when the blade is in rapid rotation during use. For a blade four (4) inches long and having a cross section area of one-quarter (1/4)

of a square inch for use in a rotor having a tip diameter of thirty-five (35) inches and rotational rate of eight thousand (8,000) R. P. M., the prestress load on the elongated rovings may be approximately one thousand fifty (1050) pounds. The prestressing is sufficient to maintain the centrifugal load on the resin of the blade within safe working limits. In other words, the pre-stress compression of the body of the blade will not be sufficiently dissipated when rotating within intended maximum speeds, to cause failure of the blade.

The compressor blades described above and illustrated in the drawings are subject to structural modification without departing from the spirit and scope of the appended claims.

Having described my invention, what I claim as new, and desire to secure by Letters Patent is:

1. A prestressed airfoil rotor blade which comprises a rigid key and pin member comprising an outer portion of key shape, a pin spaced from and substantially parallel to the outer portion, and bridging members holding the key-shaped portion and the pin in spaced relation, a plurality of prestressed elongated rovings of doublet form, each doublet having a loop at one end thereof mounted on said pin, and a cured resin impregnating the rovings to hold the rovings in tension, the blade at the doublet loops of the rovings being of key shape, the portion of the rovings remote from the pin being of airfoil configuration.

2. The method of forming a blade having airfoil surfaces, the blade having a calculated centrifugal load capacity and being composed of resin-impregnated fibres, that consists in laying resin-impregnated fibres in a mold having a cavity shaped to the configuration of the blade, stressing the fibres in tension in a direction lengthwise of the mold cavity to a load at least equal to the calculated load capacity, closing the mold on the stressed fibres, and, while maintaining said tensile load, heating the fibres to a temperature at which the resin sets.

3. The method of forming a cured resin airfoil rotor blade having prestressed fibre glass reinforcement and a rigid metal root key and pin member which comprises impregnating glass fibres with a resin, forming a doublet of said glass fibres about the root key and pin member, placing said glass fibres and root key and pin member in a die cavity, stressing the fibres in tension substantially normally to the axis of the key and pin member and setting the resin while the glass fibres are stressed and molding the resin between dies to mold the resin and glass fibres to an airfold blade shape.

4. A prestressed airfoil rotor blade which comprises a rigid key and pin member comprising an outer portion of key shape, a pin spaced from and substantially parallel to the outer portion, and bridging members holding the key-shaped portion and the pin in spaced relation, a plurality of prestressed, elongated rovings of doublet form, each doublet having a loop at one end thereof mounted on said pin, a cured resin impregnating the rovings to hold the rovings in tension, the blade at the doublet loop of the rovings being of key-shape, and a mass of resin-impregnated short staple fibre glass forming a skin surrounding the prestressed rovings, the portion of the blade remote from the pin being of airfoil configuration.

5. The method of forming a cured resin airfoil rotor blade having prestressed fibre glass reinforcement and a rigid metal root key that comprises impregnating rovings of glass fibres with a phenol-formaldehyde resin, forming a doublet of said impregnated rovings to provide a loop at one end thereof, inserting a root pin through the loop, stressing the rovings in tension in a direction normal to the axis of the pin, covering said rovings and pin with a phenol-formaldehyde resin, applying heat and pressure to the same to impregnate the rovings and form a hard, smooth surface on the blade while the rovings are stressed in tension, and setting the resin coating on the fibres in

the rovings to a hard and infusible mass while the fibres of the rovings are in tension.

6. The method of forming a cured resin airfoil rotor blade having prestressed fibre glass reinforcement and a rigid metal root key that comprises impregnating rovings of glass fibres with a phenol-formaldehyde resin, forming a doublet of said impregnated rovings to provide a loop at one end thereof, inserting a root pin through the loop, stressing the rovings in tension in a direction normal to the axis of the pin, and covering said rovings with a mixture of phenol-formaldehyde resin and short staple glass fibres, and, while the rovings are in tension, applying heat and pressure to the same to impregnate the rovings and form a hard, infusible resin blade and root surface.

7. The method of forming a cured resin airfoil rotor blade having prestressed fibre glass reinforcement and a rigid metal key and pin member, that comprises impregnating rovings of glass fibres with a phenol-formaldehyde resin, forming a doublet of said impregnated rovings to provide a loop at one end thereof, inserting a root key and pin member through the loop, placing said rovings and member in a die cavity, stressing the rovings in tension in a direction normal to the axis of the root key and pin member, injecting an injectable phenol-formaldehyde resin molding compound into the die cavity through a gate under pressure, and applying heat to the mold to set and cure the resin while the rovings are stressed in tension to a hard, infusible mass throughout the blade and the rovings, and form a hard, smooth surface on the blade.

8. A method of forming an airfoil rotor blade which comprises forming a core of elongated, substantially parallel resin-impregnated rovings in a mold cavity having a root end and a blade portion, the rovings extending lengthwise of the blade portion, stressing said rovings in tension in a direction normal to the axis of the root end and lengthwise of the blade portion of the mold cavity, injecting short fibre resin-impregnated injectable rovings through a gate into said mold cavity around said elongated rovings to fill the root end of the cavity while the rovings are stressed, and curing the resin to form a hard, smooth blade surface, whereby the resin holds the rovings in tension.

9. A method of forming an airfoil rotor blade which comprises forming a core of elongated substantially parallel resin-impregnated rovings in a mold cavity having a root end and a blade portion, the rovings extending lengthwise of the blade portion and into the root end, the elongated rovings partially filling the mold cavity, stressing the rovings in tension in a direction normal to the axis of the root end and lengthwise of the blade portion of the mold cavity, injecting short fibre resin-impregnated injectable rovings through a gate into said mold cavity around the elongated rovings to fill the mold cavity around the elongated rovings while the rovings are stressed in tension, and curing the resin to form a hard smooth blade surface, whereby the resin holds the rovings in tension.

10. A method of forming an airfoil rotor blade which comprises forming a core of elongated resin-impregnated rovings with a return bend at one end of the core about a transverse pin, the rovings extending from the pin into substantially parallel parts, the rovings being disposed in a mold cavity having a root end portion and an elongated vane-forming portion with the return bend in the root end portion of the cavity and the parallel parts extending lengthwise of the vane-forming portion, stressing the elongated rovings in tension in a direction normal to the axis of the transverse pin, injecting short staple resin-impregnated injectable rovings through a gate into said mold cavity and around the elongated rovings while the rovings are stressed, and curing the resin to form a hard, smooth blade surface, whereby the resin holds the elongated rovings in tension.
